UNITED STATES PATENT OFFICE.

ANTON KNEIP, OF MASPETH, ASSIGNOR TO HIMSELF, AND JOHN J. REED, OF BROOKLYN, NEW YORK.

RAILROAD-SWITCH.

SPECIFICATION forming part of Letters Patent No. 513,944, dated January 30, 1894.

Application filed October 12, 1893. Serial No. 487,986. (No model.)

To all whom it may concern:

Be it known that I, ANTON KNEIP, a citizen of the United States, residing at Maspeth, in the county of Queens and State of New York, 5 have invented new and useful Improvements in Railroad-Switches, of which the following is a specification.

This invention relates to an improvement in railroad switches by which the switch can 10 be conveniently actuated from the car as set forth in the following specification and claims and illustrated in the annexed drawings, in which—

Figure 1 is a plan view of the switch. Fig. 15 2 is a section along xx Fig. 1. Fig. 3 is a section along yy Fig. 1. Fig. 4 is a section along zz Fig. 1.

A is the main line or rails switching off into branches A' A'' , and B is the switch which 20 when in the position shown in full lines leads onto branch A' and in the position shown in dotted lines onto branch A'' . The switch B is set by arm or slide C having a depending prong D. As one side or the other of prong 25 D is struck by the heads E the slide C is moved to shift the switch one way or another. The heads E are connected to levers F fulcrumed at G and having their end portions formed or bent into tappets H extending upward above the ground so that when the inclined face I carried by rod K strikes a tappet H the lever F is actuated. The rod K is 30 conveniently formed as a treadle depressed into working position against the action of spring L by the foot of the attendant standing on the car or platform M. Each car can have two rods K for the two levers F or each car can have but one rod K actuating one of the levers F so as to set the switch correctly 35 40 for each particular car.

The tappets H are made to extend into grooves N in a cover or protecting plate O said plate having its upper surface raised or placed at such height that the tappets cannot 45 rise above said upper surface so that a cart or other object passing over the plate cannot strike the tappets and thus accidentally actuate the switch while the treadle K has its actuating face of such width as to readily enter a 50 groove N to act on a tappet.

The prong D is shown with oppositely inclined faces, and the levers F are adapted to act respectively on the opposite faces of the prong, each lever having its head provided with an inclined face so as to secure ready 55 sliding of the head along a face of the prong.

What I claim as new, and desire to secure by Letters Patent, is—

1. The combination with a switch, of a slide connected to the switch, a prong projecting 60 downwardly from said slide and provided with oppositely inclined faces, and pivoted actuating levers arranged on opposite sides of the prong, each of said levers being provided at one end with a head having an inclined face 65 adapted to strike the adjacent face of the prong and at its other end with a tappet adapted to be operated from the car, substantially as described.

2. The combination with a switch, of a slide 70 connected to the switch, a wedge-shaped prong projecting downwardly from said slide, and actuating levers arranged upon each side of said prong and pivoted between their ends, each of said levers being provided at one end 75 with a head having an inclined face adapted to strike the adjacent face of the prong and at its other end with a tappet adapted to be operated from the car, substantially as described.

3. The combination of a switch, a slide connected thereto, a wedge-shaped prong projecting downwardly from said slide, and actuating levers arranged on opposite sides of said prong, each of said levers being provided at 85 one end with a head having an inclined face adapted to strike the adjacent face of the prong and at its other end with a tappet adapted to be operated from the car, said levers being fulcrumed near the ends opposite the 90 heads, whereby said heads are normally held depressed by gravity and the tappets maintained elevated, substantially as described.

In testimony whereof I have hereunto set my hand in the presence of two subscribing 95 witnesses.

ANTON KNEIP.
